Des. 194,434
Patented Jan. 22, 1963

194,434

METER HOUSING

Robert L. Whitman, Jackson, Mich., assignor to Handley Industries, Inc., Jackson, Mich., a corporation of Michigan

Filed Dec. 11, 1961, Ser. No. 67,850

Term of patent 14 years

(Cl. D52—6)

FIG. 4

FIG. 1

FIG. 2

FIG. 3

FIG. 5

FIG. 1 is a perspective view of a meter housing showing the front, top, and right side thereof embodying my new design,

FIG. 2 is a front elevational view,

FIG. 3 is an elevational view of the right side,

FIG. 4 is a top plan view thereof, and,

FIG. 5 is a bottom view.

The undisclosed side of the meter housing is substantially the same in appearance as the side shown.

I claim:

The ornamental design for a meter housing, as shown and described.
